(57) **CLAIM**

The ornamental design for a roller die press, as shown and described.

DESCRIPTION

FIG. 1 is a perspective view of the roller die press;
FIG. 2 is a perspective view of the roller die press;
FIG. 3 is a front side view of the roller die press;
FIG. 4 is a back side view of the roller die press;
FIG. 5 is a left side view of the roller die press;
FIG. 6 is a right side view of the roller die press;
FIG. 7 is a top side view of the roller die press; and,
FIG. 8 is a bottom side view of the roller die press.
The broken line showing of the roller die press is included
for the purpose of illustrating portions of the roller die press
and forms no part of the claimed design.
